UNITED STATES PATENT OFFICE

160,564

BOTTLE CARRIER

Oscar L. Vines, New York, N. Y.

Application March 24, 1948, Serial No. 145,309

Term of patent 14 years

(Cl. D58—5)

To all whom it may concern:

Be it known that I, Oscar L. Vines, a citizen of the United States, residing in New York city, county of New York, and State of New York, have invented a new, original, and ornamental Design for a Bottle Carrier, of which the following is a specification, reference being had to the accompanying drawing, forming part thereof.

In the drawing:

I claim:

The ornamental design for a bottle carrier, as shown.

OSCAR L. VINES.
